UNITED STATES PATENT OFFICE

THOMAS H. HALTON, OF PHILADELPHIA, PENNSYLVANIA, ASSIGNOR TO THOMAS HALTON'S SONS, OF PHILADELPHIA, PENNSYLVANIA, A FIRM COMPOSED OF THOMAS H. HALTON AND THOMAS HALTON, JR.

CARD STRIPPER FOR JACQUARD MECHANISM

Application filed April 11, 1930. Serial No. 443,436.

This invention relates to a device for stripping cards from the card cylinder of the jacquard mechanism of a loom.

The principal object of the invention is to construct the card stripper in such a manner that the cylinder may be readily removed from the loom for repairs, etc., without disturbing the general relation existing between the cylinder and the stripper, after the stripper has once been properly adjusted with respect to the cylinder, so that the cylinder may be replaced in the loom and immediately placed in operation without requiring any additional adjustment between the cylinder and the card stripper.

The detail construction and operation of the device will be fully disclosed hereinafter, reference being had to the accompanying drawings, of which:

Fig. 1 is a sectional elevation through the card cylinder of a jacquard mechanism, showing the card stripper cooperating with the cylinder to strip the cards therefrom;

Fig. 2 is an outside end elevation showing the cylinder-supporting head at one end of the jacquard mechanism;

Figs. 3, 4 and 5 constitute a detached perspective view of the preferred form of card stripper;

Fig. 6 is an elevation of a modified form of the invention; and

Figs. 7 to 11 inclusive constitute a detached perspective view of the device shown in Fig. 6.

In Figs. 1 and 2, I have shown sufficient of an ordinary jacquard mechanism to illustrate the application of my invention thereto. This mechanism comprises usual horizontally disposed and axially reciprocable rods 1, located at each end of the card cylinder 2, the two rods being adapted jointly to support and reciprocate the card cylinder laterally, in a horizontal plane, so that the string of cards α carried by the cylinder will be brought successively into co-operating relation with the needles (not shown) of the jacquard mechanism.

On the end of each rod 1 is a head 3 provided with upper spaced flanges 4 and 5, and lower spaced flanges 6 and 7, which extend

inwardly toward the adjacent end of the cylinder 2, providing an upper guideway 8 and a lower guideway 9 for the respective halves 10 and 11 of a split bearing 12 in which the trunnion 13 of the cylinder 2 is rotatably mounted, at each end of the cylinder.

The head 3 is also provided with a vertical slot 14, within the lower guideway 9, for the reception of an end plate 15 formed integral with and on the lower half 11 of the split bearing 12. Threaded into the end plate 15 is an adjusting screw 16 which bears against the end of the trunnion 13 for adjusting the cylinder 2 axially.

Loosely mounted on the screw 16 is a clamp plate 17 which bears against the outer surface of the head 3 and is adapted to be clamped thereto by a lock nut 18 threaded onto the screw 16.

Vertical adjustment of the lower half 11 of the split bearing 12 is effected by means of an adjusting screw 19, threaded through a bridge portion 20 of the head 3 formed at the lower end of the slot 14 therein, a lock nut 21 securing the screw 19 in its adjusted position.

The upper half 10 of the bearing 12 is adapted to be raised in its guideway 8 sufficient to permit the trunnion 13 of the cylinder 2 to be raised out of the lower half 11 of the bearing 12 and then moved laterally through the passage space 22 formed between the lower end of the upper guide flange or rib 4 and the upper end of the lower guide flange or rib 6, thereby permitting the complete removal of the card cylinder 2 from the jacquard mechanism.

The upper half 10 of the split bearing 12 is held in place by a bolt 23 extending through a vertical slot 24 formed in the upper guideway 8 between the guide flanges 4 and 5. The securing bolt 23 is provided with a head 25 which clamps against the outside surface of the head 3, wings 26, 26 being provided on the head 25, to permit the locking bolt 23 to be tightened or loosened at will.

Adjustably secured by bolts 30, 30 to the head 3, at each end of the jacquard mechanism, is an inverted T-shaped racket 31 hav-

ing a slot 32 formed in the leg 33 thereof, through which the bolts 30, 30 pass.

In each of the opposite ends of the cross-arm 34 of the T-shaped bracket are card-separating rods or bars 35 and 36 respectively, the rod 36 being laterally adjustable in a horizontal slot 37 formed in the arm 34, lock nuts 38 being provided on the end of the rod 36 at each side of the arm 34 to secure the rod in its adjusted position.

The mechanism so far described is that of an ordinary jacquard mechanism and forms no part of the present invention per se.

The present invention consists in the provision of one or more, preferably two, 15 grooves cut in the cylinder 2, preferably one adjacent each of the respective ends thereof and inside the end edges of the string of cards α passing around the cylinder 2, one of said grooves being shown at 50 in Fig. 1. As 20 shown in Fig. 1, the base 51 of the groove 50 is circular in form and is disposed concentric with the axis of rotation of the cylinder 2.

The groove 50 is adapted to receive the ends 52 and 53 of arms 54 and 55 of a Y-shaped yoke element 56 which is provided with a hub 57 located on the card separating rod 36, and secured in place thereon by a set screw 58, in the preferred form of the invention.

The arms 54 and 55 are substantially equal in thickness and are adapted to be disposed in the same general vertical plane extending transversely of the cylinder 3, the groove 50 therein being slightly wider than the thickness of the ends 52 and 53 of the arms 54 and 55 respectively so that when the card stripper is properly adjusted relative to the cylinder 35 the flat sides of the arms 54, 55 will not contact with the side walls of the groove 50 and the extreme ends of the arms 54, 55 are curved substantially concentric with the base 51 of the groove 50, as shown at 59 and 60, and are spaced from the base 51 of the said 40 grooves at all times, as shown in Fig. 1.

Obviously, as the cylinder 3 is rotated to bring a new card into alignment with the needles of the jacquard mechanism, or for 45 any of the many reasons common in weaving, the cards leaving the cylinder will be positively stripped from the cylinder by contacting with either the arm 54 or the arm 55 of the stripper, depending upon the direction 50 of rotation of the cylinder.

It frequently occurs that the string of cards for one or another reason will stick to the cylinder and become damaged by being rolled around the cylinder instead of moving off the cylinder tangentially, thus the 55 reason for providing the card stripper.

As shown in Figs. 1, 3, 4 and 5, the arm 55 is pivotally mounted on the arm 54 by means of a bolt 61 provided with a butterfly nut 62 by which the arm 55 is adapted to

be clamped in place on the arm 54, the arm 55 being offset at its lower end as indicated at 63, to provide an overlap extending over the arm 54 to provide a hinge joint between the two arms.

In order to correctly position the movable arm 55 with respect to the stationary arm 54, the said stationary arm is provided with a shoulder 64 against which a similar shoulder 65 on the movable arm 55 bears, when the 75 arms are in correct relation to each other, as shown in Fig. 1.

From the above description, it will be obvious that when the cylinder 3 is to be removed from the jacquard mechanism, in the 80 manner above noted, the butterfly nut 62 is loosened, permitting the movable arm 55 to fall from its full line position to its broken line position, a shoulder 66 on the arm 55 striking the side of the arm 56 and thereby 85 supporting the movable arm in its inoperative position.

It is to be understood that the cylinder and card stripper had been correctly adjusted with respect to each other prior to the removal of the cylinder from the jacquard mechanism, thus when the cylinder or another cylinder having grooves formed therein which are identical with those in the cylinder just removed, is placed in the jacquard mechanism it is only necessary to lower the top halves 10, 10 of the split bearings 12, 12 into contact with the cylinder trunnions 13, 13, and then swing the movable arms 55, 55 back into place until the shoulders 65 thereon engage the shoulders 64 on the stationary arms 54, to make the jacquard mechanism ready for immediate use, it being understood that the bolts 23 are tightened to hold the bearing parts 10, 10 in place and the butterfly nuts 62, 62 tightened to hold the movable arms 55, 55 in place.

In Figs. 6 to 11 inclusive, I have illustrated a modified form of the invention in which the arms 54^a and 55^a are formed rigid and integral with the leg portion 56^a of the stripper. The leg 56^a is slotted, as at 70, for the reception of a vertical guide rib 71 formed on a block 72 which is adapted to be threaded onto the card-separating rod 36, and to be locked thereto by a set screw 73, a clamp plate 74 and a nut 75 being provided on the rod 36 to force the side 76 of the leg 56^a into frictional contact with shoulders 77, 77 formed on the stationary block 72. Vertical movement of the Y-shaped yoke member is governed by a set screw 78, carried by the said Y-shaped stripper and adapted to engage the lower side of the stationary element 72.

For removal of the cylinder 3, when using the device shown in Figs. 6 to 11, it is only necessary to loosen the nut 75 whereupon the entire stripper will drop clear of the cylinder, permitting the cylinder to be moved laterally out of the jacquard mechanism, the 130

same as when using the stripper shown in Figs. 1 to 5 inclusive.

Obviously, when the cylinder has been replaced in the jacquard mechanism, the stripper shown in Fig. 6 is raised until the set screw 78 engages the lower side of the stationary element 72. The stripper arms 54^a, 56^a are then in correct position in and with respect to the grooves 50 in the cylinder permitting immediate operation of the cylinder without further adjustment being necessary between the parts.

I claim:

1. The combination of a card cylinder having a circumferential groove formed therein, and a card stripper comprising a stationary element adapted to be adjusted to and permanently secured in a predetermined position relative to the cylinder and a movable section supported by the permanent section and adapted to be readily moved with respect to the permanent section and the cylinder, said movable section having a portion adapted to enter the groove in the cylinder, and co-operating stops on the permanent and movable sections respectively for correctly positioning the groove-entering portion of the movable section in said groove.

2. The combination of a card cylinder having a circumferential groove formed therein, and a card stripper comprising a stationary element adapted to be adjusted to and permanently secured in a predetermined position relative to the cylinder and a movable section supported by the permanent section and adapted to be readily moved with respect to the permanent section and the cylinder, said movable section having a portion adapted to enter the groove in the cylinder, and co-operating stops on the permanent and movable sections respectively for correctly positioning the groove-entering portion of the movable section in said groove, and means for securing the movable section in its operating position on said permanent section.

3. The combination of a card cylinder having a circumferential groove formed therein, means supporting said cylinder for rotation about a definitely located axis, a bar rigidly supported by the cylinder-supporting means in substantially parallel spaced relation to the axis of rotation of said cylinder, a card stripper comprising a section carried by said bar and adapted to be permanently secured on said bar in a predetermined relation to the groove in the cylinder, and a section movably carried by said permanent section and having a portion adapted to enter and lie within the groove in the cylinder.

4. The combination of a card cylinder having a circumferential groove formed therein, means supporting said cylinder for rotation about a definitely located axis, a bar rigidly supported by the cylinder-supporting means in substantially parallel spaced relation to

the axis of rotation of said cylinder, a card stripper comprising a section carried by said bar and adapted to be permanently secured on said bar in a predetermined relation to the groove in the cylinder, a section movably carried by said permanent section and having a portion adapted to enter and lie within the groove in the cylinder without engaging the walls thereof, and co-operating stops on the movable and permanent sections respectively for so positioning the movable section in the cylinder groove.

5. The combination of a card cylinder having a circumferential groove formed therein, means supporting said cylinder for rotation about a definitely located axis, a bar rigidly supported by the cylinder-supporting means in substantially parallel spaced relation to the axis of rotation of said cylinder, a card stripper comprising a section carried by said bar and adapted to be permanently secured on said bar in a predetermined relation to the groove in the cylinder, a section movably carried by said permanent section and having a portion adapted to enter and lie within the groove in the cylinder without engaging the walls thereof, co-operating stops on the movable and permanent sections respectively for so positioning the movable section in the cylinder groove, and means for securing the said movable section in its operating position relative to the permanent section and the cylinder.

6. The combination of a card cylinder having a circumferential groove formed therein, means supporting said cylinder for rotation about a definitely located axis, a bar rigidly supported by the cylinder-supporting means in substantially parallel spaced relation to the axis of rotation of said cylinder, a card stripper comprising a section carried by said bar and adapted to be permanently secured on said bar in a predetermined relation to the groove in the cylinder and having a rigid arm extending into the groove at one side of the axis of said cylinder, and an arm pivotally mounted on said permanent section and adapted to enter the groove at the opposite side of the axis of the cylinder.

7. The combination of a card cylinder having a circumferential groove formed therein, means supporting said cylinder for rotation about a definitely located axis, a bar rigidly supported by the cylinder-supporting means in substantially parallel spaced relation to the axis of rotation of said cylinder, a card stripper comprising a section carried by said bar and adapted to be permanently secured on said bar in a predetermined relation to the groove in the cylinder and having a rigid arm extending into the groove at one side of the axis of said cylinder, an arm pivotally mounted on said permanent section and adapted to enter the groove at the opposite side of the axis of the cylinder, and co-operat-

ing stops on the stationary and movable arms respectively for correctly positioning the movable arm relative to the stationary arm.

8. The combination of a card cylinder having a circumferential groove formed therein, means supporting said cylinder for rotation about a definitely located axis, a bar rigidly supported by the cylinder-supporting means in substantially parallel spaced relation to the axis of rotation of said cylinder, a card stripper comprising a section carried by said bar and adapted to be permanently secured on said bar in a predetermined relation to the groove in the cylinder and having a rigid arm extending into the groove at one side of the axis of said cylinder, an arm pivotally mounted on said permanent section and adapted to enter the groove at the opposite side of the axis of the cylinder, co-operating stops on the stationary and movable arms respectively for correctly positioning the movable arm relative to the stationary arm, and means for clamping the movable arm to the stationary arm.
